UNITED STATES PATENT OFFICE

118,848

DESIGN FOR A CAN OPENER

Myron J. Zimmer, Chicago, Ill., assignor to The Edward Katzinger Company, Chicago, Ill., a corporation of Illinois

Application September 30, 1938, Serial No. 80,146

Term of patent 14 years

To all whom it may concern:

Be it known that I, Myron J. Zimmer, a citizen of the United States, residing at Chicago, in the county of Cook and State of Illinois, have invented a new, original, and ornamental Design for a Can Opener, of which the following is a specification, reference being had to the accompanying drawing, forming part thereof.

Fig. 1 is a side elevational view of a can opener showing my new design.

Fig. 2 is an end elevation thereof viewed from the rear end of the handle members.

Fig. 3 is a perspective view.

The dominant feature of the design resides in the portion shown in full lines.

I claim:

The ornamental design for a can opener, as shown and described.

MYRON J. ZIMMER.
